FIG. 21.

FIG. 1 is a top plan view of a molded packaging tray for meat or the like showing our new design;

FIG. 2 is a bottom plan view;

FIG. 3 is a side elevational view;

FIG. 4 is an end elevational view;

FIG. 5 is an enlarged sectional view thereof taken along the line 5—5 of FIG. 1;

FIG. 6 is a top plan view showing a second embodiment of our new design;

FIG. 7 is a bottom plan view;

FIG. 8 is a side elevational view;

FIG. 9 is an end elevational view thereof;

FIG. 10 is a top plan view showing a third embodiment of our new design;

FIG. 11 is a bottom plan view;

FIG. 12 is a side elevational view;

FIG. 13 is an end elevational view thereof;

FIG. 14 is a top plan view showing a fourth embodiment of our new design;

FIG. 15 is a bottom plan view;

FIG. 16 is a side elevational view;

FIG. 17 is an end elevational view thereof;

FIG. 18 is a top plan view showing a fifth embodiment of our new design;

FIG. 19 is a bottom plan view;

FIG. 20 is a side elevational view thereof; and

FIG. 21 is a side elevational view thereof.

The characteristic feature of the design resides in the high inverted V-shaped ribs crossing at right angles and forming a bottom of substantial height with plural open windows, together in combination with narrow, steep walled staggered ribs at the periphery which merge into the end and side walls of the tray as shown.

We claim:

The ornamental design for a molded packaging tray for meat or the like, as shown and described.
